ELASTIC FLUID TURBINE

Stanley Smith Cook and Louis Mortimer Douglas,
Wallsend-on-Tyne, England, assignors to The
Parsons Marine Steam Turbine Company, Lim-
ited, Wallsend-on-Tyne, England

Application March 4, 1940, Serial No. 322,194
In Great Britain March 4, 1939

3 Claims. (Cl. 253—67)

This invention relates to elastic fluid turbines of the double flow type in which the direction of flow is in opposite directions in the two sections.

With such turbines of conventional construction, the duplicate flows are usually similar in every respect and symmetrically disposed about a transverse plane at mid length.

With such construction and with the rotor restrained axially by the thrust or adjusting block at one end in the usual manner, when thermal changes occur in the operation, resulting in differential expansion between turbine and rotor, the clearances between the tips of the rotor blades and the cylinder bore are increased in one half but are diminished in the other. As a consequence additional clearance must be provided in order to enable the turbine to operate with safety.

The main object of the present invention is to provide constructions in which the clearance may be reduced without impairing safety.

The invention in brief consists in a double flow elastic fluid turbine of the type described in one flow portion of which the rotor blade tips lie in a conoidal surface, in the other flow portion the stator blade tips lie in a conoidal surface and the apices of both said conoidal surfaces lie at the same end of the turbine.

The accompanying diagrammatic drawing illustrates in vertical longitudinal section a convenient construction of turbine embodying the present invention in one form.

In carrying the invention into effect according to the form illustrated in the accompanying drawing as applied to a central flow turbine in which the capacities of the two branches are equal we provide the rotor shaft *a* at one end with a collar *b* located axially by adjustable thrust faces *cd*.

As regards the half of the rotor adjacent to the said collar, the rotor is formed as a cylindrical body *e* from which project radially the rows of blades *f* and the tips of these blades lie in a somewhat conical surface or surfaces the larger diameter of which is at the end of the rotor adjacent to the collar and the smaller diameter of which is at the middle of the length of the rotor.

The associated half *g* of the encircling stator is correspondingly coned or tapered.

As regards the other half of the rotor, the rotor is formed as a conoidal body *h* from which project radially the rows of blades *i* and the tips of these blades lie in a cylindrical surface or sur-

faces concentric with the cylindrical internal face of the stator whilst the tips of the stator blades *k* lie on a conoidal surface or surfaces closely adjacent to the external surface of the conoidal body *h*.

The two conoidal surfaces are co-extensive in the arrangement shown.

With this arrangement the varying clearances, i. e., those clearances which vary with relative axial movement of rotor and stator, on the half *e* adjacent to the collar *b* are those between the tips of the moving blades *f* and the coned cylinder bore *g*, and on the other half *h* are those between the tips of the fixed blades *k* and the surfaces *j* of the coned rotor. In this case relative axial movement of rotor and stator causes all the said clearances to be affected in the same way, that is, they are all diminished or all increased, with the result that they may be set to have a minimum value when the greatest axial displacement has taken place and may be arranged so that under any other conditions these clearances increase. For instance, if the rotor expands more than the stator when heated up to full power service conditions, then the thrust block faces *cd* will be so adjusted that the radial blade clearances are a minimum under those full power service conditions.

At any other conditions where the thermal expansion is less the rotor will retract from the stator towards the collar and these blade clearances will all increase.

Should it be that the rotor expands less than the stator, then it would be necessary to put the thrust block at the opposite end, that is to say to dispose the conoidal surfaces so that their apices lie at the same end of the turbine as the device for axially controlling the rotor relatively to the stator.

In this case again the thrust block may be set so that the radial blade clearances are at their minimum values under full power service conditions, i. e., when the temperature is at a maximum; under any lower temperature conditions these clearances would increase.

In the example described above with reference to the accompanying drawing, the diameter of the annulus *m* between the rotor and stator of one half of the turbine is substantially equal near the inlet region to the annulus *n* of the other half, but if desired these annuli may instead be made substantially equal at the outlet ends.

Again, the two conoidal surfaces *g*, *j* instead of

being co-extensive may be of different diameters at both ends.

The capacities of the two flow passages may be different if desired and in cases where they are so arranged that the axial thrusts on the rotor do not balance, dummies or other balancing devices may be employed in order to relieve the axial force on the thrust block.

In all cases it is advisable to have a little residual thrust in one direction in order definitely to locate the axial position of the rotor relatively to the stator. Preferably the residual thrust is such as to tend to reduce the clearances. The residual thrust is preferably obtained by making the appropriate section greater in capacity or in diameter or in both capacity and diameter than the other section.

We claim:

1. A double flow elastic fluid turbine embodying a casing, two opposed-flow stator sections in said casing, inward projections constituting stator blades on each section, a rotor body lying in both sections, outward projections on the rotor constituting rotor blades in each section, the surface containing the tips of the rotor blades of one section being conoidal and the surface containing the stator blades of that section being cylindrical, the surface containing the rotor blades in the other section being cylindrical and the surface containing the stator blades of that section conoidal and the apices of the two said conoidal surfaces lying at the same end of the turbine.

2. A double flow elastic fluid turbine embody-

ing a casing, two opposed-flow stator sections in said casing, inward projections constituting stator blades on each section, a rotor body lying in both sections within the tips of the said projections, outward projections on the rotor constituting rotor blades in each section, the surfaces containing the tips of the blades being in one section conoidal in the case of the rotor blades and cylindrical in the case of the stator blades and in the other section cylindrical in the case of the rotor blades and conoidal in the case of the stator blades and the apices of the two said conoidal surfaces lying at the same end of the turbine.

3. A double flow elastic fluid turbine embodying a casing, two opposed-flow stator sections in said casing, inward projections constituting stator blades on each section, a rotor body lying in both sections, outward projections on the rotor constituting rotor blades in each section, the surface containing the tips of the rotor blades of one section being conoidal and the surface containing the stator blades of that section being cylindrical, the surface containing the rotor blades in the other section being cylindrical and the surface containing the stator blades of that section conoidal, a thrust or axial-adjustment device for one end of said rotor body, the apices of both conoidal surfaces lying at the end of the turbine remote from that at which the said thrust or axial-adjustment device is disposed.
